UNITED STATES PATENT OFFICE.

WILLIAM H. GARLOCK AND WILLIAM J. STUBBE, OF SEATTLE, WASHINGTON.

SLICING-MACHINE.

1,266,450.

Specification of Letters Patent. Patented May 14, 1918.

Application filed October 1, 1917. Serial No. 194,112.

To all whom it may concern:

Be it known that we, WILLIAM H. GARLOCK and WILLIAM J. STUBBE, citizens of the United States, residing at Seattle, in the county of King and State of Washington, have invented certain new and useful Improvements in Slicing-Machines, of which the following is a specification.

This invention relates to slicing machines; 10 the object of the invention is to provide an inexpensively operated and efficient machine whereby the slicing of bread, fish or other articles may be performed with despatch and uniformity.

15 In some respects the present invention is in the nature of an improvement upon the machine disclosed in U. S. Patent No. 1,212,045, issued to us January 9, 1917, and to which reference may be had.

20 As compared with the prior machine, the principal features of the present invention consist in the novel loaf-feeding means; devices for holding the work down upon the table to accommodate any inequalities in the thicknesses or shapes of the loaves; improved 25 manner of assembling and regulating the cutting knives; and guiding means for directing the slices of bread from the knives.

The invention further consists in the novel 30 arrangement and combination of parts, as will be hereinafter described and claimed.

In the accompanying drawings, Figure 1 is a longitudinal section of a machine embodying the present invention. Fig. 2 is a 35 plan view of the same, shown partly in section through 2-2 of Fig. 1. Fig. 3 is a fragmentary view partly in section and partly in perspective, said section being taken through 3-3 of Fig. 2. Fig. 4 is a 40 transverse vertical section taken substantially through 4-4 of Figs. 1 and 2. Fig. 5 is a fragmentary plan view of the complementary knife frames. Fig. 6 is a front elevational view of a portion of one of said 45 knife frames. Fig. 7 is a sectional view through 7-7 of Fig. 6. Fig. 8 is a perspective view of a part of one of the work-feeding attachments. Fig. 9 is a detail longitudinal elevational view of one of the frame 50 members. Fig. 10 is a sectional view through 10-10 of Fig. 9.

Supported upon a suitable framework 1 of the machine is a table comprising parts 2 and 2¹ which are longitudinally spaced 55 to accommodate a plate 3 therebetween. At each side of the frame is a slotted post 4

which serve as guides for vertically movable frames or sashes carrying gangs of serrated cutter knives 5. Each of said sashes is formed with side rails 6 and horizontal top and bottom rails 7 and 8, respectively. Said top and bottom rails are provided with transversely arranged slots 7¹ and 8¹ to accommodate shanks 9 and 9¹ of knife attachments having bifurcated heads 10 and 10¹ 60 into which extend the ends of the respective knives which are secured thereto by pins 11. The shanks 9 and 9¹ are screw-threaded for nuts 12 and 12¹ whereby the heads 10 and 10¹ are secured in adjusted positions 65 laterally of the respective sashes.

Extending downwardly through the slots 7² of the upper rail 7 of each sash (see Figs. 5 and 6) are adjustment screws 13 engaging in screw-threaded holes provided in the 75 shanks 9 whereby the elevation of the upper heads is adjusted to regulate the tension of the knives.

The cutting edges 5¹ of the various knives of both sashes are arranged in a vertical 80 plane indicated by x-x in Figs. 1 and 5. Said knife-carrying frames or sashes are reciprocated to move simultaneously in opposite directions, as by means of eccentrics 14-14¹ on a power-driven shaft 15, said eccentrics having their rods 16-16¹ connected at their upper ends by pins engaging in apertured ears 17 depending from said sashes.

Below the table 2 is provided a conveyer 90 comprising endless chains 18 disposed adjacent to opposite sides of the table and passing about guide rolls 19 and 19¹ which are mounted upon shafts 20 and 20¹ journaled in the girder members 21 constituting a part of 95 the aforesaid supporting framework 1, said chain being driven by means of sprocket wheels 22 secured to a transverse shaft 23. The latter has mounted thereon a pulley 23¹ about which passes a belt 25 from a pulley 100 15¹ on the shaft 15.

Extending through the journal bearings provided in links 18¹ of said chain, are transverse rods 26 to which are secured radially disposed pins or spurs 27 adapted to 105 extend through slots 28 provided in the table part 2 to penetrate the bread or other article being sliced, and effect the feeding movement thereof.

The action of said spurs is regulated by 110 means of controllers provided on the ends of the rods 26, each having two studs 29

and 30 of unequal lengths, the longer and heavier ones 29 being preferably disposed to have their axes in a plane with the axes of spurs 27 while the other studs are preferably disposed in planes rectangular thereto.

The shorter studs 30 acting as crank elements and guided in ways 31, cause the heavier and longer arms to be carried above a track element 32 provided above said ways on the inner side of each of the frame girder members 21. As the various spurs approach into proximity of the slicing knives, they are withdrawn from the work by being carried downwardly with the chain about sheaves 19¹ and during which the prongs are caused to slope rearwardly by means of curved guide plates 34, one on each side, being engaged by the respective studs 29.

As illustrated in Figs. 4 and 10, the ways 31 are of insufficient depths to allow the studs 29 to enter therein. The plate 3, as best shown in Fig. 3, is seated at its forward and rear ends upon flange elements 35 and 36 provided on the table parts, the forward end of said plate being sloped, as at 37, to engage against a correspondingly sloped edge of table part 2 while being held down by screws 38 at the side and rear of the plate.

At the front edge, said plate is formed with comb-like teeth 39 and afford therebetween slots 39¹ through which operate said slicing knives, while at the rear thereof and in axial alinement with the respective slots are slots 40 through which protrude disks 41 carried by an arbor 42 journaled in bearings, not shown, provided on the underside of the plate 3.

Included in the invention are presser devices for holding down upon the plate 3 the work as it traverses the same. Such pressure devices, as best shown in Figs. 1 and 4, comprise a number of rings 43 mounted upon transverse bars 44 and 44¹ of less diameter than the openings within said rings and supported from their ends in boxes 45 and 45¹ movable vertically in guides 50 provided in branches 46 and 46¹ of the posts 4.

47 represent springs acting to yieldingly hold the boxes 45 and 45¹ and the associated bars 44 and 44¹ in their lowermost positions.

The operation of the invention may be explained as follows:—

The operator standing in front of the machine places the articles to be sliced, such as a loaf of bread indicated by L in Fig. 4, upon the front end of the table, whereupon the conveyer prongs 27 engage in the loaves and feed the same toward and through the sashes carrying the knives 5 to be sliced thereby, the slices thus produced being pushed ahead onto the table part 2¹. Dur-

ing such action the conveyer prongs are successively brought into operative engagement with the loaves at the front end of the table and are thence progressively moved thereby by the traveling prongs until the latter are withdrawn, as before explained.

While passing through the knife sashes, the loaves are firmly held down on the table part 2 and plate 3 by means of rings 43 which, at the higher portions of the loaves, are resiliently held thereagainst by means of rods 45 which are urged downwardly by the springs 47.

By reason of the rings being loosely mounted upon said bars 44-44¹, they will accommodate themselves to any irregularities or low places in the loaves, as will be understood from an inspection of Fig. 4.

When being sliced, the disks 41 extending into the interstices between the slices, will serve to direct them fairly upon the delivery part 2¹ of the table. When it is desired to change the thicknesses of slices, the plate 3 is removed and the knives 5 are shifted laterally into desired positions after loosening nuts 12-12¹ and screws 13. Being thus adjusted, another plate such as 3, in which the slots 39 and the disk 41 are properly spaced, is inserted in lieu of the one removed.

In the present embodiment of our invention, the cutting edges of the knives of both sashes are arranged to be substantially in the same transverse vertical plane and in consequence the opposite movements of the two gangs of knives will have no effect either to raise or lower the articles being sliced, the pressure rings 43 serving to steady the articles as they travel through the sash.

The operation and advantages of the invention will, it is thought, be understood from the foregoing.

What we claim, is—

1. In a slicing machine, cutter knives, a frame for said knives comprising side bars and top and bottom rails, said rails being provided with horizontal slots, knife-attaching heads having screw-threaded shanks extending through the respective frame rails, means for adjusting the vertical positions of the heads with respect to the upper frame rail, and nuts engageable with said shanks to secure the heads in both vertical and horizontal adjustments.

2. In a slicing machine, cutter knives, two knife-carrying frames disposed one in front of the other, each of said frames being formed of side bars and top and bottom rails, knife-engaging heads adjustably connected to the respective frame rails, said heads being arranged to extend rearwardly and forwardly, respectively, from the rails of the front and rear frames to present the cutting edges of the knives of both frames

in the same vertical plane, guides for said frames, and means to reciprocate the frames simultaneously in opposite vertical directions.

5 3. In a slicing machine, the combination with slicing knives, vertically movable frames carrying said knives, means provided in said frames for regulating the relative lateral positions of the knives, of a 10 table having an opening therein, a plate removably secured in the table opening, said plate being provided with slots extending from its front edge to accommodate said knives, and enable the plate being removed 15 or attached to the machine without disturbing said knives.

4. In a slicing machine, the combination with slicing knives, vertically movable frames carrying said knives, means provided in said frames for regulating the relative lateral positions of the knives, of a 20 table having an opening therein, a plate removably secured in the table opening, said plate being provided with slots extending 25 from its front edge to accommodate said knives, and a series of rotary disks extend-

ing through slots of said plate and serving to guide and retain the slices produced by said knives in upright positions.

5. In a slicing machine, the combination 30 with a table, cutting knives arranged for vertical movements, means to actuate said knives, and a conveyer to feed articles to be sliced to said knives, of presser devices provided in proximity to said knives for 35 holding the articles down upon the table while being fed to said knives through the agency of said conveyer, said presser devices comprising a vertically movable horizontal bar, rings having apertures of greater 40 diameter than said bar and through which the latter extend, and springs serving to yieldingly hold said bar in its lowermost position.

Signed at Seattle, Washington, this 25th 45 day of September, 1917.

WILLIAM H. GARLOCK.
